UNITED STATES PATENT OFFICE.

WILLIAM J. MILLER, OF SWISSVALE BOROUGH, PENNSYLVANIA.

MECHANISM FOR FORMING GLASSWARE.

1,409,621.

Specification of Letters Patent. Patented Dec. 20, 1921.

Application filed December 16, 1918. Serial No. 266,910.

To all whom it may concern:

Be it known that I, WILLIAM J. MILLER, a citizen of the United States, and residing in the borough of Swissvale, in the county of Allegheny and State of Pennsylvania, have invented or discovered new and useful Improvements in Mechanism for Forming Glassware, of which the following is a specification.

10 My invention consists in a new and improved machine for pressing glassware, and means for mounting the same in connection with the tank or other container of molten glass.

15 The object in view is the provision of automatic mechanism of this character which will produce pressed glassware at great speed and in large quantities, thus greatly reducing the cost of manufacture and increasing the output.

20 Generally speaking, the machine consists of a series of molds, pivotally mounted and flexibly connected together; means for moving said series intermittently to bring said molds in turn into the pressing position; means for shearing the glass deposited into the molds; pressing mechanism, and means for tilting the molds to discharge the pressed ware.

25 I also show means for increasing or decreasing the number of molds in the series, as may be required.

30 I also show a new and improved mounting for the machine in connection with the glass tank, which greatly facilitates the operation of the machine.

35 Novel features of construction and arrangement of parts will appear from the following description.

40 In the accompanying drawings, which are intended merely to illustrate a practical embodiment of the principles of my invention without limiting the scope of the same to the construction shown, Figure 1 is a side elevation of a machine, embodying my invention, shown mounted on the front of a glass tank; Fig. 2 is a top plan view of the same, the tank being shown in broken horizontal section; Fig. 3 is an enlarged longitudinal section taken along the line III—III in Fig. 2; Fig. 4 is an enlarged cross section taken along the line IV—IV in Fig. 2; Fig. 5 is a partial side elevation of the machine with the left hand cover plates removed; Fig. 6 is an

enlarged broken vertical section showing in 55 detail the pressing plunger and follower, the section being taken at right angles to that in Fig. 4 and the mechanism being shown depressed to engage one of the molds; Fig. 7 is a plan view of one of the molds, showing its 60 mounting in the flexible side chains; Figs. 8, 9, 10 and 11 are, respectively, inside face views of the lower left hand cover plate, the lower right hand cover plate, the upper left hand cover plate and the upper right hand 65 cover plate; Fig. 12 is a detailed view in plan showing the depending loop of the mold carrier and the stirrup mounted thereon, and Fig. 13 is a plan view on smaller scale than Fig. 2 and better illustrating the mounting 70 of the machine in relation to the tank.

75 Referring to the accompanying drawings, I will first proceed to describe the structure of the machine itself, and then its mounting in relation to the glass tank.

A represents a pair of side frames connected together by means of a horizontal bed block B through which and through said frames pass the stay bolts 1, the ends of said bolts being seated in countersunk recesses in 80 the outer faces of the frames. 2 represents vertical flanges at either side of the block forming horizontal tracks. C is a shaft journaled transversely of the machine in the frames and block, and at either end, outside 85 of said frames, said shaft has rigidly mounted thereon a cam 3 or 4, the cam 3 being wider than the cam 4 and provided with a perimetral flange 5 to prevent the accidental slipping off of the eccentric strap to be described. Outside of the cam 3 the shaft C is provided with a worm wheel 6 meshing with the worm collar 7 on the driven shaft D mounted longitudinally of the machine. The sides of the machine are inclosed by lower 90 cover plates E and E' which are bolted in place to the frames A.

95 The shaft C ends at the outer hub of the wheel 6 and said hub is provided with a concentric series of sockets 8 engaged by a similar series of studs 9 on the inner face of disk 10 which revolves in a circular hole 11 in the cover plate E. 12 is a stuffing box bolted to the outside of the plate E having its bore concentric with but of less diameter than the 100 said hole, so that the outer face of the disk bears against the inner end of the stuffing box, said disk being kept in close resilient 105

contact with said stuffing box by means of a helical spring 13 seated in a shallow bore 14 in the end of shaft C. 15 is a stub shaft extending axially from the disk 10 through the 5 stuffing box and having a cam wheel 16 adjustably fixed on its outer end. It is evident that a grease and oil-tight joint is obtained between the cover plate E and the extension of the shaft C, thus preventing the escape of 10 lubricant.

10 I show the said cam 16 used for operating the shear mechanism to be later described, but the same may be used for actuating other 15 of the elements of the machine, as may be found convenient.

F is a cross-head guide in the form of an annular sleeve which is bolted or otherwise secured to the tops of the frames A and serves as a top brace for the same. The bore of said 20 guide is differential, the larger bore being above. In the upper bore is slidably mounted the cross-head G provided with radial wrist pins 19 which extend through vertical slots 20 in the cross-head guide F and are 25 pivotally engaged by the upper ends of the eccentric straps 21 whose lower ends encircle the cams 3 and 4 on the shaft C, whereby the revolution of the shaft C reciprocates the cross-head G. The upper ends of the straps 30 21 move in vertical depressions or grooves 22 in the sides of the cross-head guide, which grooves are inclosed by the top cover plates H and H' which are bolted or otherwise secured to the cross head-guide and the side 35 frames. The lower edges of the cover plates H and H' fit down on and make a tight fit with the top edges of the cover plates E and E', respectively. The driving shaft D may be suitably journaled in boxes 23 formed on 40 the abutting edges of the cover plates E and H.

I is the plunger or pressing element provided with an internal water chamber 24. Said plunger is provided with an axial contracted and threaded throat 25 which forms the inlet port for said chamber, the outlet 45 ports 26 of said chamber being of smaller size and arranged in concentric series about said throat. 27 is the plunger shaft which is externally threaded and screwed into the throat 25, and whose axial bore forms the water inlet passage. The outer end of said 50 shaft bore is countersunk and threaded for the attachment of the flexible water inlet pipe 28. An annular head 29 is screwed onto the upper end of the shaft 27, having its lower end tapered to fit into the flared upper bore of the tubular plunger holder 30 whose bore fits loosely about the shaft 27 and whose 55 lower end bears on the plunger I. An eccentrically located port 31 through the head 29 connects with the annular space between the shaft and holder and has its outer end countersunk and threaded for the attachment of 60 a flexible pipe 32. This forms the outlet for

the water from the chamber 24 through the ports 26.

The holder 30 is exteriorly threaded and its lower end is screwed into a collar 33. To prevent accidental disengagement of the collar from the holder, I may flare the lower extremity of the holder and the bore of the collar, as shown.

34 is a perimetral flange on the collar 33 which is adapted to engage from below an 75 internal flange of the bottom spring plate 35 which bears on the annular plunger follower 36 surrounding the plunger I. The follower 36 is provided with an internal top flange 37 which is engaged from below by 80 the shoulder 38 of the plunger after the plunger starts its ascent, thus causing the follower to first lag behind and then ascend with the plunger. 39 is an annular water passage in the follower 36 which is intersected at one point by a cross partition 40 on either side of which a threaded port extends through the outer wall of the follower to the water passage. Into said ports are screwed 85 the pipes 41, for which clearance is provided by one of the vertical apertures 42 in the base of the cross-head guide F. Flexible water pipes 43 connect with the outer ends of the pipes 41 for the admission of water into and the escape of water from the passage 39, 90 thus cooling said follower.

44 is a helical spring coiled about the plunger holder, its lower end bearing on the collar 33, while its upper end bears against the upper spring plate 45. A second helical 100 spring 46 is coiled about the spring 44, and preferably is of less strength than the latter, its lower end bearing on the spring plate 35 while its upper end bears on the spring plate 45.

105 The upper spring plate 45 is a split spring annulus which loosely encircles the plunger holder and is expanded into tight contact with the cross-head G by means of a tapered and threaded plug 47 which is screwed into 110 a tapered and threaded hole vertically intersecting the split in the ring 45. Thus by unscrewing the plug, the ring may be loosened from the cross-head and adjusted in relation thereto, and by screwing up the plug, the 115 ring may be rigidly fixed in position in the cross-head.

48 represents wing nuts screwed down on the holder 30 to compress the helical springs.

To prevent the holder 30 from turning in 120 relation to the shaft 27, a feather or key 49 is seated in alined recesses cut in the plunger and plunger holder.

The mold carrier comprises a pair of endless side chains made up of links 50 detachably pivoted together, as by means of pins or other members 51. Thus the chains may be lengthened or shortened, as desired, by the introduction of or removal of the proper 125 number of links. The chains run in vertical 130

planes relative to the machine and are supported by means of pulley 52 journaled on stub shafts extending inwardly from the side frames A at either end of the machine. 5 The horizontal portions of the chains between the pulleys 52 run along the tops of the flanges 2 of the block B and preferably beneath undercut ledges 53 in the faces of the side frames to prevent buckling. At the 10 rear of the machine said chains are engaged from below by pulleys 54 loosely mounted on stub shafts 55 extending from the frames A. Thus the chains are doubled up to encircle about half of the perimeter of the rear pulleys 52.

J represents a plurality of molds, preferably of circular form, pivotally mounted at regular intervals between the side chains. Said molds are provided with two 20 diametrically opposed, radial trunnions 56 which are journaled in bushings 57 which are substituted for the pins for connecting together the adjacent ends of the chain links, the ends of said bushings being upset to 25 prevent their slipping out of engagement with said links.

It is evident that the length of the chains and the number of molds mounted thereon may be easily regulated as circumstances 30 may require.

K is a table or platen mounted horizontally on the block B between the frames A and beneath the pressing mechanism. Thus the molds move along over said table beneath 35 the pressing mechanism. The rear end of said table is curved downwardly, as at 58, to form an incline to assist the molds in riding up onto the table as the chains move counterclockwise.

40 The method of imparting intermittent movement to the series of molds is as follows. 59 represents ears depending from the straps 21, horizontally pierced for pivotal attachment of links 60 whose other ends are pivoted to levers 61 intermediate of the latter. The lower ends of levers 61 are pivoted to blocks 62 sliding in seats 63 on the outer faces of frames A, while the upper ends of said lever are pivoted to bars 64 45 sliding in grooves 65 on the outer faces of said frames. 66 is a cross-head whose ends are journaled in the ends of bars 64, and 67 represents a pair of push rods adjustably mounted in said cross-head, whose free ends 50 are curved downwardly and extend forwardly of the machine to engage the links of the carrier chains. As the shaft C rotates, the cross-head 66 reciprocates back and forward, and during its forward movement the curved ends of the rods 67 engage the links of the chains and move the same counterclockwise, while during the rearward movement of the cross-head, said rods trail idly over the chains without moving the latter.

The free ends of the push rods 67 engage the links at the molds J, as shown in Fig. 3, and the forward movement of the push rods moves the mold so engaged into the pressing position. The force is thus applied to the mold, instead of to the links intermediate of the molds, so that wear in the links does not interfere with spotting the molds accurately under the pressing position and any buckling of the carrier chains 75 is avoided. The push of the rods on the molds may be regulated by adjusting the rods in the cross head thus compensating for any wear and enabling the molds to be accurately spotted. 80

The inwardly extending ends of the stub shafts 55 are flattened on top so that the inner end of the chute L may be bolted thereto, the chute being outwardly and downwardly inclined, as shown, and its inner 85 end protruding sufficiently to engage the molds as they rise to pass over the pulleys 54, so that said molds are upset and their contents dumped into the discharge chute. By positioning the trunnions 56 above the 90 center of gravity of the loaded mold, said molds retain their upright position throughout their travel except when engaged by the inner end of the discharge chute. Then the molds are upset and their contents discharged, but said molds immediately 95 reverse into their normal position, so that they rise up over the rear pulleys 52 with their mold cavities on top, ready to receive the gather of glass. 100

I provide a shear mechanism to cut off the neck of glass when the gatherer deposits the molten glass in the mold before it moves into the forming position under the plunger mechanism. Thus I show a 105 stationary shear blade 68 mounted on top of the cover plate E and extending over the path of the molds at the point where a mold stops before moving into the forming position. 69 is a movable blade pivoted 110 to blade 68 and open and closed at the proper intervals by means of a link 70 which connects the butt end of said blade with the upper end of a rocking lever 71 pivoted to the cover plate E and having its lower 115 end held in contact with the perimeter of the cam 16 by a spring 72.

The shaft D is provided with a belt pulley 73 for the application of power, and said pulley is loosened or tightened on said shaft 120 by means of clutch mechanism 74. 75 is a hand crank device by means of which the machine may be turned over for adjustment or repairs. Said hand crank device may be journaled in a bearing 76 preferably formed 125 in an extension of the cover plate E.

The general operation of the machine is as follows:

Any suitable means or method of depositing glass in the molds before they are spotted 130

in the forming position may be adopted. Thus automatic or semi-automatic gathering mechanism may be used, but I have shown, and will hereafter describe the employment 5 of a gatherer for that purpose.

As the molds in turn reach the station next before the pressing station a gather of molten glass is deposited in the waiting mold and neck of the glass sheared by the closing 10 of the shear blades. By the next movement of the carrier the loaded mold is positioned under the pressing mechanism, which descends, the following 36 first seating on the top of the mold and covering the outer rim 15 of the mold cavity. The plunger I then descends into the mold cavity and presses the glass into the desired form. When the cross-head G starts to ascend the plunger I lags behind, remaining in the mold until the spring 20 ring 45 strikes against the nuts 48, said ring having descended out of contact with said nuts owing to the compression of the helical springs in forcing the plunger and plunger follower into engagement with the mold. 25 The period between the beginning of the upward movement of the cross-head and the engagement of the nuts by the ring 45 determines the dwell of the plunger in the mold. When said ring 45 strikes against 30 said nuts 48 the plunger I begins to rise out of the mold, but the follower 36 remains seated upon the mold until the shoulder 38 on the plunger engages from below the flange 37 on the follower, thus causing the 35 follower to rise with the plunger. The lag of the follower behind the plunger enables the former to hold the pressed ware in the mold until the plunger is stripped or disengaged therefrom, thus preventing the pressed 40 ware from rising out of the mold with the plunger. The tension of the springs 44 and 46 determines the resilient force with which the plunger and follower engage the mold, said force being adjusted by means of the 45 nuts 48, so that the design of mold in use will be properly filled by the descent of the plunger into the same. Thus a deep mold will require more force to fill than will a shallow mold.

If the spring ring 45 were not adjustable, as already described, in the cross-head G, the screwing down of the nuts 48 to increase the compression of the helical springs would serve to elevate the plunger and follower in 50 relation to the cross-head, and likewise the unscrewing of said nuts to reduce the compression of the helical springs would depress the plunger and follower in relation to the cross-head, thereby rendering the proper 55 positioning of the pressing mechanism to suit various heights or characters of molds impossible. By first adjusting the nuts 48 on the holder 30 so that the desired compression is given to the helical springs, and then 60 unscrewing the plug 47, and thus loosening 65

the ring 45 in the bore of the cross-head G, then moving the ring 45 up or down in the cross-head to obtain the proper elevation of the plunger and follower, to properly engage the mold when depressed, and then screwing 70 up the plug 47 to again tighten the ring 45 into rigid engagement with the cross-head, this difficulty may be overcome and the plunger and follower given the proper elevation and movement. 75

Upon the next movement of the carrier, after the pressing operation, the mold now containing the pressed ware passes forwardly, and then step by step downwardly and then upwardly, always retaining its upright position through gravity, until it engages the chute L which upsets the mold and dumps its contents into the chute, the mold then rerighting as it approaches and mounts the table K once more. 80

The forward movement of the molds takes place during the latter part of the upward movement of the pressing mechanism and during the first part of its downward movement, thus clearing the molds of the pressing mechanism during the movement of the molds. 90

As stated the number of molds may be varied by the addition to or subtraction from the chain links and molds. Where the length of the chains causes them to loop down to a relatively great degree below the machine, there might be a tendency for the descending molds to strike against the ascending molds or of the chains to swing laterally and strike the sides of the machine. I avoid this difficulty by using a stirrup M whose cross bar 77 is preferably weighted and whose upwardly extending legs are outside of the carrier chains. The upper ends 95 of said legs are provided with inwardly extending stub shafts upon which are journaled the rollers 78 which ride upon the side chains and thus support the stirrup. This provision lengthens the chord of the arc of 100 the depending chain loops and prevents the molds interfering with each other, and the weight of the stirrup keeps the chains and molds in proper vertical alignment. The 105 roller riding upon the chains prevent the stirrup mounting upwardly through the movement of the chains toward the discharge chute. 110

My novel method of mounting the machine in connection with the glass tank 115 or other container of molten glass is particularly advantageous. The machine is mounted on the front or extension of the tank in such a manner that the gatherer stands facing the tank with the machine in 120 front of him so that the required movements, to introduce his punty into the furnace for a supply of glass and deposit such supply into the waiting mold to be sheared from the punty, are reduced to a minimum. Thus the 125 130

lower cover plate E' is provided with stout hook members 79 which hook over a horizontal beam or support 80 on the front of the glass tank N. Thus the machine which 5 is of small compass and compact construction is supported in place with the mold into which the glass is to be placed directly in front of the ring hole 81. I prefer to provide a sheet metal shield O which is attached to the front of the furnace about the opening 81 and whose sides and top are inclosed, said shield extending over the machine table K and the station assumed by the mold for the gather operation. The top 10 of said shield is curved downwardly and forwardly to protect the face of the gatherer, who stands at P, Fig. 13, and is provided with a vertical slot 82 through which the gatherer inserts his punty to obtain glass from the tank and deposit it in the mold. Thus the gatherer is protected from the heat and glare of the furnace and the glass is prevented from chilling when it is placed in the mold. The gatherer can work much 15 more rapidly with this arrangement as he does not need to move his feet and the movement of the punty is reduced to a minimum.

The cover plates may be provided with oil inlet ports 83, closed by screw plugs, so that 20 grease or oil may be introduced between the cover plates and the side frames, thereby providing a bath of lubricant in which the moving parts of the machine operate. As shown in Fig. 3, I prefer to form one or more 25 of the bolts 1, which hold the side frames A to the block B, as hollow cylinders whereby a cross equalizing passage for lubricant between the two sides of the machine is formed, for the better circulation of the lubricant.

40 The advantages of my improved machine are manifold. Among them may be mentioned the following.

The machine is relatively small and very compact. It is easily portable, and therefore 45 can be shifted from one furnace or tank to another as factory requirements may dictate. Its actuating parts are inclosed in baths of lubricant, thus facilitating operation and reducing wear. Molds for producing 50 any character of pressed ware may be used in the machine and the number of the molds mounted in the carrier may be reduced or increased without otherwise changing the machine or impairing the efficiency.

55 The method of mounting the machine is such that a single operator or gatherer is required, no boys or assistants being needed. If mechanical gathering means be substituted for manual gathering the operation of 60 the machine becomes entirely automatic. The pressing mechanism may be adjusted for the proper forming of the glass in any character of mold, whether shallow or deep. The molds remain upright throughout their 65 travel, except when upset by the discharge

chute, and then, after discharging their contents into the chute, the molds right themselves automatically before approaching the gathering position.

The action of the push rods directly on 70 the molds enables the molds to be at all times accurately spotted under the pressing mechanism and prevents unnecessary wear on the carrier chains.

Although, for the sake of clearness, I have 75 minutely described the embodiment of the principles of my invention illustrated in the drawings, I do not limit myself thereby, but claim broadly:

1. In a machine for manufacturing articles of glass, the combination of forming means, a carrier intermittently revolving in a vertical plane beneath said forming means, and a plurality of molds pivotally mounted on said carrier and adapted to be presented 80 in turn to said forming means, the pivotal axes of said molds being above their centers of gravity whereby said molds normally retain their upright position.

2. In a machine for manufacturing articles of glass, the combination of forming means, a flexible carrier intermittently revolving in a vertical plane beneath said forming means, and a plurality of molds pivotally mounted on said carrier and adapted to 90 be presented in turn to said forming means, the pivotal axes of said molds being above their centers of gravity whereby said molds normally retain their upright position.

3. In a machine for manufacturing articles of glass, the combination of forming means, a carrier intermittently revolving in a vertical plane beneath said forming means, a plurality of molds pivotally mounted on said carrier and adapted to be presented in 100 turn to said forming means, and means intercepting the path of said molds and adapted to upset them in turn for the discharge of their contents, the pivotal axes of said molds being above their centers of gravity 110 whereby said molds automatically right themselves after the discharge of their contents.

4. In a machine for manufacturing articles of glass, the combination of forming means, a flexible carrier revolving in a vertical plane beneath said forming means, a plurality of molds pivotally mounted on said carrier and adapted to be presented in turn 115 to said forming means, and means intercepting the path of said molds and adapted to upset them in turn for the discharge of their contents, the pivotal axes of said molds being above their centers of gravity whereby said molds automatically right themselves 120 after the discharge of their contents.

5. In a machine for manufacturing articles of glass, the combination of forming means, a horizontal support beneath said forming means, a flexible carrier, intermit- 130

tently revolving in a vertical plane, traversing said support, and a plurality of molds pivotally mounted on said carrier and adapted to be presented in turn on said support to said forming means, the pivotal axis of said molds being above their centers of gravity whereby said molds normally retain their upright position during their travel.

6. In a machine for manufacturing articles of glass, the combination of forming means, a horizontal support beneath said forming means, a flexible carrier, intermittently revolving in a vertical plane, traversing said support, a plurality of molds pivotally mounted in said carrier and adapted to be presented in turn on said support to said forming means, and means intercepting the path of said molds beneath said support adapted to upset said molds for the discharge of their contents, the pivotal axes of said molds being above their centers of gravity whereby said molds automatically right themselves before mounting said support.

25 7. In a machine for manufacturing articles of glass, the combination of forming means, a pair of endless chains revoluble in vertical planes beneath said forming means, a plurality of molds mounted on said chains and adapted to be presented in turn to said forming means, a power driven reciprocating member, and push rods mounted on said member and adapted to engage and revolve said chains intermittently.

35 8. In a machine for manufacturing articles of glass, a horizontal support beneath said forming means, a pair of endless chains revolvably mounted in vertical planes, the upper portions of said chains traversing said support, a plurality of molds pivotally mounted on said chains, a power-driven reciprocating member, and push rods mounted on said member and adapted to engage and revolve said chains intermittently.

45 9. In a machine for manufacturing articles of glass, the combination of a support, a cross-head slidably mounted on said support, a pressing plunger, an annular plunger follower, and a pair of concentric helical springs having their one ends bearing against said cross-head while their other ends bear against said plunger and said follower, respectively.

55 10. In a machine for manufacturing articles of glass, the combination of a support, a cross-head slidably mounted on said support, a spring plate mounted on said cross-head, a plunger holder extending through said plate, a plunger and a plunger follower mounted on one end of said holder, a nut screwed on the other end of said holder against said plate, and a pair of helical springs interposed between said plate and the said plunger and follower, respectively.

60 65 11. In a machine for manufacturing arti-

cles of glass, the combination of a support, a cross head slidably mounted on said support, a spring plate adjustably mounted on said cross-head, a plunger holder extending through said plate, a plunger and a plunger follower mounted on one end of said holder, a nut screwed on the other end of said holder against said plate, and a pair of helical springs interposed between said plate and said plunger and follower, respectively. 75

12. In a machine for manufacturing articles of glass, the combination of a support, a cross-head slidably mounted on said support, a spring plate mounted on the cross head, a plunger holder extending through said plate, a plunger and a plunger follower mounted on one end of said holder, a nut screwed on the other end of said holder against said plate, and a pair of concentric helical springs coiled about said holder between said spring plate and said plunger and holder, respectively. 85

13. In a machine for manufacturing articles of glass, the combination of a support, a cross-head slidably mounted on said support, a spring plate adjustably mounted on said cross-head, a plunger holder extending through said plate, a plunger and a plunger follower mounted on one end of said holder, a nut screwed on the other end of said holder against said plate, and a pair of concentric helical springs coiled about said holder between said spring plate and said plunger and holder, respectively. 90

14. In a machine for manufacturing articles of glass, the combination of a support, a cylindrical cross-head slidably mounted on said support, an annular spring plate mounted in the bore of said cross-head, a plunger holder extending through said plate, a plunger and plunger follower mounted on one end of said holder, a nut screwed on the other end of said holder against said plate, and a pair of concentric helical springs coiled about said holder between said plate and said plunger and follower, respectively. 105

15. In a machine for manufacturing articles of glass, the combination of a support, a cylindrical cross-head slidably mounted in said support, a split spring ring inserted in the bore of said cross-head, a plunger holder extending through said ring, a plunger and a plunger follower mounted on one end of said holder, a nut screwed on the other end of said holder against said ring, 115 a pair of concentric helical springs coiled about said holder and bearing against said ring and said plunger and follower, respectively, and means for expanding said ring to lock said ring into fixed engagement 120 with the bore of said cross-head. 125

16. In a machine for manufacturing articles of glass, the combination of a driven shaft, a support, a cross-head sliding on said support, a forming element mounted on 130

said cross-head, a pair of cams on said shaft, and eccentric straps mounted on said cams and pivotally attached to said cross-head.

17. In a machine for manufacturing articles of glass, the combination of a support provided with a longitudinal aperture, a cross head reciprocating in said support, a pressing plunger depending from said cross-head, a plunger follower depending from 10 said cross-head and surrounding said plunger, said follower being provided with a fluid passage, and an inlet pipe and an outlet pipe, extending through the aperture in said support into the said passage of said follower.

18. In a machine for manufacturing articles of glass, the combination of a pair of spaced apart side frames, a mold carrier revolvable in a vertical plane between said side frames, forming mechanism reciprocating in a vertical plane between said side frames, a driven shaft journaled transversely in said side frames with its ends protruding therefrom, operative connections 25 between the ends of said shaft and said carrier and said forming mechanism, respectively, and cover plates inclosing said connections.

19. In a machine for manufacturing articles of glass, the combination of a pair of spaced apart side frames, a mold carrier revolvable in a vertical plane between said side frames, forming mechanism reciprocating in a vertical plane between said side frames, a driven shaft journaled transversely in said side frames with its ends protruding therefrom, operative connections 35 between the ends of said shaft and said carrier and said forming mechanism, respectively, cover plates inclosing said connections, shearing mechanism, and operative connection between one end of said shaft and said shearing mechanism, said last named connection extending through an oil-tight 40 bearing in the cover-plate.

20. In a machine for manufacturing articles of glass, the combination of a pair of spaced apart side frames, a mold carrier revolvable in a vertical plane between said side frames, forming mechanism reciprocal 50 in a vertical plane between said side frames, a shaft journaled transversely of said machine having its ends protruding beyond said side frames, operative connection be-

tween the ends of said shaft and said carrier and said forming mechanism, respectively, and a lubricant bath for said operative connection.

21. The combination with a glass tank provided with a ring hole, of a glass forming machine, supported on the front of the tank and having a carrier revolvable in relation to the machine, a plurality of molds mounted on said carrier, and means for revolving said carrier intermittently to bring 65 said molds in turn in front of said ring hole to receive molten glass prior to the forming operation.

22. The combination with a glass tank provided with a ring hole, of a glass forming machine adjacent to said tank and having a revolvable carrier, a plurality of molds mounted on said carrier, means for revolving said carrier, intermittently to bring 70 said molds in turn in front of said ring hole to receive molten glass, and a shield surrounding said ring hole and extending outwardly to cover the molds when the latter are in the receiving position.

23. The combination with a glass tank 80 provided with a ring hole, of a glass forming machine supported on the front of said tank and having a revolvable carrier, a plurality of molds mounted on said carrier, means for revolving said carrier intermittently to bring 85 said molds in turn in front of said ring hole to receive molten glass, and a shield surrounding said ring hole and extending outwardly to cover the molds when the latter are in the receiving position. 90

24. The combination with a glass tank provided with a ring hole, of a glass forming machine supported at the front of said tank, and a shield over said ring hole and extending forwardly from said tank over 95 said machine to protect the gatherer from the heat of said ring hole.

25. The combination with a glass tank provided with a ring hole, of a glass forming machine supported at the front of said tank, and a shield over said ring hole and extending forwardly from said tank over 100 said machine, said shield being provided with an aperture at the front for the insertion of the gatherer's punt. 105

Signed at Swissvale, Pa., this 12th day of December, 1918.
